UNITED STATES PATENT OFFICE.

BERNHARDT JORGENSEN, OF BEVERLY, MASSACHUSETTS, ASSIGNOR TO UNITED SHOE MACHINERY CORPORATION, OF PATERSON, NEW JERSEY, A CORPORATION OF NEW JERSEY.

MACHINE FOR WORKING UPPERS OVER LASTS.

1,423,613.

Specification of Letters Patent.

Patented July 25, 1922.

Application filed November 25, 1918. Serial No. 264,038.

To all whom it may concern:

Be it known that I, BERNHARDT JORGENSEN, a subject of the King of Denmark, residing at Beverly, in the county of Essex and State of Massachusetts, have invented certain Improvements in Machines for Working Upper Over Lasts, of which the following description, in connection with the accompanying drawings, is a specification, like reference characters on the drawings indicating like parts in the several figures.

This invention relates to machines for use in the manufacture of boots and shoes for working uppers over lasts. In the manufacture of some kinds of shoes, such for example as one type of rubber-soled shoe commonly known as "sneakers", it is the usual practice to secure the upper in conformity to the contour of the last by causing the margin of the upper to adhere to the insole, for example by the use of cement. An object of the invention is to provide an improved machine adapted for use in the manufacture of shoes of this type for working the upper over the last and securing it, but it will be understood that the invention is not limited in respect to utility to the manufacture of this particular kind of shoe nor to the manufacture of shoes in which the soles or other parts are made of rubber.

Rubber-soled shoes of the kind above-mentioned are usually made with a comparatively thin insole which is shaped from a rubber compound and which is not vulcanized until after the lasting operation on the shoe. During the operation of conforming the upper to the last the insole is in a comparatively soft and yielding condition, and for this reason it is necessary to avoid any action upon the shoe materials such as to wrinkle the insole or to displace it from the edge of the last. Because of this condition the operation of lasting shoes of this kind has been performed heretofore very largely by hand.

This invention provides a machine so constructed as to perform its operations upon the shoe without danger of displacement of the insole relatively to the last, the term "insole" being used herein as a generic term to indicate that part of the shoe to which the upper is secured to hold it in conformity to the contour of the last irrespective of the type of the shoe. The invention is herein

shown as embodied in a machine in which the means for working the upper over the last comprises means for pulling over the upper and means for lasting the forepart of the shoe, but in its broader aspects the invention is not limited to a combination of pulling-over means and lasting means nor restricted with respect to the portion of the shoe upon which the operations may be performed.

A feature of the invention consists in a novel construction and arrangement of means for working an upper over a last and for securing it to the insole by adhesion, the machine herein shown having overlaying means constructed to bend the margin of the upper inward over the insole without substantial pressure against the insole such as would tend to displace it, and means for pressing the margin down into position to adhere to the insole. In the illustrative machine the overlaying means comprises members which are similar in construction and use to end embracing wipers of prior pulling-over and lasting machines, and for convenience these members will accordingly be referred to herein as wipers, although in the use of the present machine they are operated in such relation to the shoe as to gather and bend the margin of the upper inward without substantial overlaying pressure. Combined with these overlaying members or wipers in the illustrative construction are presser members which are movable in paths transverse to the plane of the insole for engagement with that portion of the margin of the upper which projects farther inward than the wipers to press the margin against the insole, the construction shown having means for directing these members in paths which are inwardly inclined toward the shoe bottom to cause them to engage the upper with a tendency to pull it inward from the edge of the shoe and thus to eliminate any wrinkles and to tighten the upper on the last.

In addition to the novel feature above set forth, the invention also presents novelty in the construction and arrangement of means for pressing the margin of the upper against the insole irrespective of other constructional features of the machine, and in a novel combination of different means including a roll or rolls for overlaying differ-

ent adjacent portions of the margin of the upper.

The various features of the invention, including certain details of construction and combinations of parts, will now be described with reference to the accompanying drawings and pointed out in the claims.

In the drawings,

Figure 1 is a view partly in side elevation and partly in vertical section of the head portion of a pulling-over and lasting machine in which the invention is embodied;

Fig. 2 is a view substantially in front elevation, with parts in section, showing the side grippers and other mechanism for operating upon the shoe at the sides of the forepart;

Fig. 3 is a detail perspective view of a portion of the mechanism shown in Fig. 2 for overlaying the margin of the upper and pressing it into position to adhere to the insole at one side of the forepart of the shoe;

Fig. 4 is a view in elevation showing more in detail a portion of the mechanism shown in Fig. 3;

Fig. 5 is a plan view partly in section showing the mechanism for effecting and controlling operative movement of the lasting devices;

Fig. 6 is a perspective view of portions of the lasting and shoe positioning mechanisms, and

Fig. 7 shows the forepart of a shoe operated upon by the use of the machine.

The machine herein shown embodies in its general organization many of the features of a type of machine shown and described in United States Letters Patent No. 1,280,613, granted on Oct. 2, 1918 upon an application of Orrell Ashton, to which reference may be made for a more complete understanding of various details of the construction of machines of the illustrative type not hereinafter specifically described. The machine is provided with a sole rest 2 against which the bottom of the insole on the last is positioned when the work is presented to the machine, and with a heel rest 4 which is moved automatically up into supporting engagement with the heel end of the shoe after the machine is started. For pulling the upper the machine includes a toe gripper 6 and side grippers 8 connected respectively to updraw levers 10 and 12 mounted on a pivot rod 14, the toe gripper lever 10 being operated yieldingly from a cam on a cam shaft 16 through a spring 18 and the side gripper levers 12 being similarly operated through springs 20. The pulling of the upper is effected by the operation of the gripper levers assisted by a slight downward swinging movement of the sole rest 2 effected by means of a cam 22 on the cam shaft 16, the machine then coming to rest with the

upper held under tension to permit the work to be inspected by the operator and any necessary adjustment of the upper on the last to be made, as for example by manipulation of the updraw levers 10 and 12. The machine is also provided with side clamp arms 24 which are swung inward toward the shoe when the machine is again started and carry clamping pads 26 for engagement with the sides of the shoe adjacent to the edge 75 of the shoe bottom and other clamping members 28 which engage the shoe farther downwardly in position to assist in supporting the shoe against subsequent downward pressure upon the shoe bottom.

Similarly to the machine shown and described in the prior patent, above mentioned, the machine herein shown is provided with wiper mechanism carried by a front arm 30 mounted to swing in directions lengthwise 85 of the shoe, this mechanism comprising two sets of end embracing wipers adapted respectively to operate upon right and left shoes. The different wipers are mounted on opposite ends of a bracket 32 which is slotted lengthwise to permit limited relative movement of the wipers and the arm 30 in directions lengthwise of the shoe. A spring 34 (Fig. 1) mounted on a rod projecting downwardly from the end of the arm 30 through 90 the slot in the bracket 32 tends to maintain the bracket in its adjusted relation to the arm while permitting the above-mentioned limited relative movement between the two parts and also permitting the bracket to be 100 swung about the end of the arm to position the wipers at either end of the bracket alternatively for operation upon a shoe.

Each set of wipers comprises a pair of end plates 36 pivoted at 38 on a support 40 which is secured to the bracket 32. These plates are held normally in open position by means of springs 42, the limit of their opening movement being determined by engagement of pins 44 thereon with a plate 46 which is 110 movably mounted on the support 40 and is adapted for use by the operator in positioning the wipers relatively to the shoe and in partially closing them in preparation for their advance over the shoe bottom. Pivotally mounted on the plates 36 are extension members 48 which project beyond the ends of the plates 36 and serve as continuations of said plates to operate upon portions of the upper at the sides of the toe 120 and rearwardly along the forepart of the shoe. The connections between the extension members 48 and the plates 36 permit said members to swing a limited distance relatively to said plates. Operative movement 125 of the wipers lengthwise of the shoe to cause the end plates 36 to perform their function at the end of the toe is effected by swinging movement of the arm 30, such movement being limited by engagement of an abut- 130

ment pad 31 on the bracket 32 with the end of the shoe. The closing movement of the wipers over the shoe is effected by means of side arms 50 which are similar to the side tacker arms of the machine described in said Ashton patent and carry means which will be hereinafter described more in detail for engaging the extension wiper members 48 and closing them inward over the shoe, 10 and through the action of these members for closing also the end plates 36. Movement of the arms 50 toward the shoe is limited by the engagement of stop lugs 49 on the arms with abutment shoulders 51 on the side 15 clamp arms 24.

The means for operating the arms 30 and 50 is the same as in prior pulling-over machines of the illustrative type and, briefly described, comprises a slide 52 (Figs. 1 and 20 5) connected at its front end to the arm 30 and connected also through segmental gears 54 to slides 56 which have operative connection with the side arms 50. Movement of the slide 52 in one direction thus 25 serves to swing the arms toward the shoe and its movement in the opposite direction to return the arms to starting position. The connection between the slide 52 and the arm 30 comprises spring plungers 58 at opposite sides of the arm which are carried by the slide 52 and have beveled faces to engage similarly beveled abutment faces on the arm, these plungers being arranged to yield and permit the slide to continue its 30 movement for a short distance after the arm 30 has arrived at its limit of movement toward the shoe. For the same purpose the gears 54 are connected to the slides 56 through toothed slides 60 which carry spring 35 plungers 62 having beveled faces to engage similar faces on the outer ends of the slides 56. This construction whereby the slides 52 and 60 are afforded a limited movement relatively to the arms 30 and 50 serves 40 to insure that the arms shall be advanced to their limit of movement irrespective of the size of the shoe, and also serves another purpose which will be explained more fully hereinafter.

50 For pressing the margin of the upper into position to adhere to the insole the front arm 30 carries a presser member 64 which is curved similarly to the wipers and is constructed and arranged to engage a section of the margin of the upper which projects inwardly beyond the inner edges of the intermediate portion of the wipers and press it into position to adhere to the insole. Preferably the member 64 is provided with a 55 pad 66 of leather or the like to insure effective and uniform contact with the upper material. The member 64 is secured to a pair of side plates 70 which are in turn secured to a slide 72 mounted in a slot 74 in 60 the lower end portion of the arm 30 and pro-

vided at its upper end with a pin 76 engaged by the forked lower end of an operating bar 78. As the bar 78 is moved downward operative movement is imparted to the member 64 to cause it to press the margin 70 of the upper into position to adhere to the insole. It will be noted that the guide slot 74 is inclined to the plane of the shoe bottom in such manner as to cause the member 64 to receive a component of inward movement 75 over the shoe as it moves downwardly toward the shoe, and by reason of such movement the member upon its engagement with the margin of the upper tends to pull the margin inwardly and thus to tighten the 80 upper free from wrinkles over the last.

For operating upon the margin of the upper at the sides of the toe beyond the field of action of the member 64, the side arms 50 carry each a pair of presser members 80 85 which, similarly to the member 64, are arranged to engage a portion of the margin which projects beyond the inner edge of the wipers and press it into position to adhere to the insole. Similarly to the member 64, the members 80 are faced with a pad 82 of leather or the like, the construction shown comprising a single pad 82 secured to both members 80 of each pair. The members 80 are pivoted at 81 on the lower ends of supporting bars 84 each of which is pivotally suspended at 86 on an arm 88 which is in turn pivoted at 90 on a carrier plate 92. The plates 92 are suspended on a pivot 94 carried by the arm 50 and are permitted to 90 swing relatively to the arm about this pivot as a center a limited distance determined by a stop screw 96 which extends through slots 98 in the plates. Each of the bars 84 carries a pin 100 which engages in a slot 102 in the 95 adjacent carrier plate 92, this construction serving to position the bar and the member 80 relatively to the plate 92 and to guide the member 80 in its operative movement toward the shoe. Springs 104 engaging the 100 carrier plates 92 tend to swing them about their pivot 94 in the direction of the shoe, the springs yielding more or less as the plates engage the wipers or the sides of the shoe to permit the plates to adjust themselves to the lateral contour of the shoe and thus to position the presser members 80 at the correct distance from the edge of the shoe bottom. Operative movement is imparted to the members 80 from an operating 105 bar 106 slidably mounted in the arm 50, this bar carrying a pin 108 which engages in slots in the arms 88 and thus establishes an operative connection between the bar and the arms while permitting the arms to move 110 relatively to the pin and to each other in the adjusting movement of the plates 92. It will be understood that as the bar 106 is moved downward, the arms 88 are swung about their pivot 90 and force the bars 84 and the 115 120 125 130

presser members 80 downward toward the shoe. By reference to Figs. 2 and 3 it will be seen that the slots 102 are inclined in such relation to the shoe bottom as to cause 5 the members 80, similarly to the end member 64, to engage the margin of the upper with a tendency to pull it inward and thus to tighten the upper on the last. It will be evident that the members 80 by reason of 10 their pivotal connection at 81 with the bars 84 are permitted to adjust themselves to the lengthwise contour of the shoe bottom.

It will be understood that the bar 78 for 15 operating the front presser member 64 and the bars 106 for operating the side presser members 80 are similar in construction and arrangement to the front and side tack driver bars of prior pulling-over machines, and since the mechanism for operating these 20 bars is the same as in prior machines it will be described herein only briefly. Operative movement is imparted to the bar 78 by a lever arm 110 which is operated by a torsion spring 112, and similar movement is 25 imparted to the side bars 106 by lever arms 114 operated by springs 116. Normally the bar 78 is upheld against the tension of its spring by means of a plate 118 (Fig. 5) on the slide 52 which engages under a shoulder 120 on the bar 78, and the side bars 106 are similarly upheld by plates 122 on the slides 60 which engage under shoulders 124 on the bars. The operative movement 30 of the slide 52, as hereinbefore explained, 35 serves to swing the arms 30 and 50 inwardly toward the shoe, and during this swinging movement the arms continue to be upheld in the manner above described. When the arms, however, have reached their limits 40 of movement and are stopped in the manner hereinbefore explained, the continued movement of the slides 52 and 60 serves to withdraw the plates 118 and 122 from the respective shoulders 120 and 124 on the 45 bars 78 and 106 and thus to release the bars to their operating springs and permit them to be driven downwardly to operate the presser members 64 and 80. Subsequently, in the return of the parts to starting position, the bars are uplifted again in consequence of an oscillating movement of the 50 supporting bracket 126 in which the slides 52 and 60 are mounted accompanied by outward return movement of the slides. 55 These operations are explained more in detail in prior United States Patent No. 663,777, R. F. McFeely, granted on December 11, 1900.

In order to extend the lasting operation 60 of the machine farther rearwardly on the shoe than the wipers and the presser members 80, each of the side arms 50 carries a roll 128 which is pivoted on a holder 130 slidably mounted in a guideway 132 in a 65 bracket 134, this bracket being mounted on

a pivot 136 on the arm 50. This construction permits relative movement of the arm 50 and the roll 128 toward or from the shoe and also permits the roll to swing in directions transverse to the plane of the shoe 70 bottom. A plate 138 is forked at its lower end to engage in slots in the slide 130 and also has bearing engagement with an upwardly extending arm of the bracket 134. Extending through said arm and also 75 through the plate 138 is a bolt 140 which is fast on the supporting arm 50 and carries a spring 142 bearing at one end on the plate 138 and at its other end on a nut on the end of the bolt. The spring 142 thus 80 tends to force the plate 138 toward the bracket 134 and thereby to force the roll supporting slide 130 inwardly toward the shoe, and at the same time the spring and the plate act upon the upwardly extending 85 arm of the bracket 134 with a tendency to swing the bracket about its pivot 136 and thus to depress the roll 128 relatively to the plane of the shoe bottom. In operation, the roll is carried into engagement with 90 the shoe by the inwardly swinging movement of the arm 50 while the side grippers are still holding the upper under tension as shown in Fig. 4, and as the roll is held back by resistance of the upper, the arm 50 is 95 permitted to continue its movement toward the shoe. The roll is carried first into engagement with a portion of the upper which is below the edge of the bottom of the inverted shoe, and as the movement of the 100 arm 52 continues the roll swings upwardly over the edge of the shoe bottom against the tension of the spring 142. When the grippers release the upper the spring 142 reacts and forces the roll inwardly across 105 the margin of the upper, as illustrated by Fig. 3. A substantial extent of the margin of the upper beyond the ends of the wipers is thus overlaid and pressed into position 110 to adhere to the insole.

In the operation of the machine upon a shoe such, for example, as a rubber soled shoe of the character hereinbefore described, the operator presents in the usual pulling-over position, as indicated in Fig. 1, a last 115 having assembled thereon an insole *a* of unvulcanized rubber compound and an upper *b* of canvas or similar fabric, the margin of the upper having been previously coated with cement. The operator then depresses the starting treadle of the machine, whereupon the grippers 6 and 8 seize the margin of the upper and pull it upwardly 120 in unison with a slight downward rocking movement of the sole rest 2 and by an upward movement of the heel rest 4 into supporting engagement with the rear end of the shoe. The machine now comes to rest with the upper held under tension to enable the operator to inspect the work and make 125 130

any of the usual adjustments which may be necessary. In some machines of the illustrative type all the subsequent operations upon the shoe are performed upon the second depression of the starting treadle, while in others the second depression of the treadle is followed only by the inward movement of the clamp arms 24 into holding and supporting relation to the shoe. While it is 5 practically immaterial to the present invention whether the machine operates thus in two stages or in three, it will be assumed for the purposes of explanation that the machine operates in three stages and that 10 after the side clamp arms have been swung into operative relation to the shoe, as shown in Fig. 2, the machine again comes to rest.

In the interval prior to the final depression of the starting treadle the operator, by 20 sliding the bracket 32 forwardly on the lower end of the front arm 30 and by tipping the bracket relatively to the arm against the tension of the spring 34, positions the wipers in the relation to the work which it is 25 desired that they shall assume prior to their power effected operative movement. In operating upon a shoe of the character described the wipers will be so positioned as to afford substantial clearance between them 30 and the plane of the insole, in order to avoid displacement of the margin of the insole relatively to the last through pressure of the wipers. Having positioned the wipers in the manner desired and closed them against 35 the upstanding margin of the upper by manipulation of the plate 46, the operator, by manipulating a handle 144 on the toe gripper lever 10, opens the gripper and causes it to release the margin of the upper. 40 He then depresses the starting treadle to cause the machine to complete its operation upon the shoe.

As the arms 30 and 50 are swung inward in the final stage of the cycle of operations 45 in the manner hereinbefore described, the wipers are advanced lengthwise of the shoe by the action of the arm 30 upon the bracket 32 to the limit determined by engagement of the abutment pad 31 with the end of the 50 shoe, and the middle wiper plates 36 are thus rendered effective to bend the margin of the upper inward over the insole at the end of the shoe without substantial pressure against the insole such as might tend to displace it. 55 Simultaneously the carrier plates 92 on the arms 50 engage the extension wiper members 48 and swing these members inward to bend the margin of the upper over the insole at the sides of the forepart, the members 48 through their engagement with the plates 36 serving also to swing these plates inward about their pivots 38. The carrier plates 92 by their engagement with the wipers and subsequently with the sides of 60 the shoe adjust themselves against the ten-

sion of their springs 104 in accordance with the lateral contour of the shoe and thus position the presser members 80 at the desired distance from the edge of the shoe bottom, the member 64 being similarly positioned by 70 the movement of the front arm 30. As the arms 50 are swung inward they carry the rolls 128 into engagement with the tensioned upper, as shown in Fig. 4. Before the arms 50 have completed their inward movement 75 they engage tripping devices 146 on the side grippers 8 and thus cause these grippers to release the upper, whereupon the rolls 128 are forced farther inward by the action of the springs 142 and by the continued movement of the arms 50 and press a portion of the margin or the upper which extends rearwardly beyond the ends of the wipers into position to adhere throughout its width to the insole. As soon as the arms 30 and 50 80 have arrived at their limits of inward movement, the operating bars 78 and 106 are released to the action of their springs in the manner hereinbefore explained and in their downward movement carry the presser members 64 and 80 into engagement with that portion of the margin of the upper which extends inwardly beyond the inner edge of the wipers. The presser members, as hereinbefore explained, approach the shoe in 85 paths which are inwardly inclined toward the plane of the insole, and in consequence of such movement they engage the margin of the upper with a tendency to pull it inward from the edge of the last bottom as 90 well as to press it into adhering relation to the insole and thus assist in flattening the upper under the wipers against the insole and in pulling it tightly over the last. Subsequently to this operation of the presser 95 members the parts of the machine are returned to their starting positions and the shoe is released from the machine. In consequence of the operation of the machine the forepart of the shoe is lasted and the margin of the upper is pressed evenly into adhering relation to the insole around the toe and along the opposite sides of the forepart, as indicated in Fig. 7.

The combination of upper pulling means 115 and means for rolling the margin of the upper inwardly over the insole, in its broader aspects, is not claimed herein, since it is the prior invention of W. G. Cheney claimed in application Serial No. 248,850 filed on August 8, 1918, and owned by the assignee of the present application.

Having described the invention, what I claim as new and desire to secure by Letters Patent of the United States is:

1. A machine for working an upper over a last and securing it to an insole by adhesion having, in combination, upper pulling means, means for bending the margin of the upper inwardly over the insole, said 130

- 6
- bending means being mounted for inward movement lightly along the surface of said margin without substantial pressure against the insole, and additional means constructed and arranged to engage the inwardly bent margin of the upper and to press it into adhering relation to the insole while the margin is thus lightly held by the bending means.
- 10 2. A machine for working an upper over a last and securing it to an insole by adhesion having, in combination, upper pulling means, means for bending the margin of the upper inwardly over the insole, said bending means being mounted for inward movement along the surface of said margin without substantial pressure against the insole throughout said movement, and a presser member guided for movement in a path oblique to the plane of the insole to engage and press the inwardly bent margin of the upper into adhering position to the insole.
- 15 3. A machine for working an upper over a last and securing it to an insole by adhesion having, in combination, end embracing wipers and means for operating them to gather and bend the margin of the upper inwardly over the insole without substantial pressure against the insole and to hold the margin lightly in its inwardly bent condition, and means for engaging the inwardly bent margin of the upper and pressing it into adhering relation to the insole while the margin is thus lightly held by the wipers.
- 20 4. A machine for working an upper over a last and securing it to an insole by adhesion having, in combination, overlaying means constructed and arranged to bend the margin of the upper inwardly over the insole without substantial pressure against the insole, and means constructed and arranged to engage the inwardly bent margin of the upper frictionally with pressure directed toward the plane of the insole and inwardly from the edge of the shoe bottom in substantially the same location lengthwise of said edge as the overlaying means to tighten the upper and press the margin into position to adhere to the insole.
- 25 5. A machine for working an upper over a last and securing it to an insole by adhesion having, in combination, means for laying the margin of the upper over the insole, and spring controlled means for yieldingly engaging a portion of the margin of the upper which projects farther inward over the insole than said overlaying means and pressing it into adhering relation to the insole.
- 30 6. A machine for working an upper over a last and securing it to an insole by adhesion having, in combination, a wiper and means for operating it to bend the margin of the upper inward over the insole, and means mounted for positioning movement with the wiper and arranged to engage a portion of the margin of the upper which projects inward beyond the inner edge of said wiper and to press said margin into adhering relation to the insole.
- 35 7. A machine for working an upper over a last and securing it to an insole by adhesion having, in combination, a member mounted for movement to bend the margin of the upper inwardly over the insole, a presser device for engaging a portion of the inwardly bent margin of the upper projecting farther inwardly than said bending member and for pressing it into adhering relation to the insole, a guide along which said device is movable bodily toward the plane of the insole, and power operated mechanism for imparting operative movements to said bending member and presser device.
- 40 8. A machine for working an upper over a last and securing it to an insole by adhesion having, in combination, end embracing wipers and means for operating them to gather the margin of the upper round the end of the shoe and lay it over the insole, and presser members arranged in a series along the wipers and constructed and arranged to engage the margin of the upper beyond the inner edges of said wipers and to press said margin into adhering relation to the insole.
- 45 9. A machine for working an upper over a last and securing it to an insole by adhesion having, in combination, end embracing wipers and means for operating them to work a substantially continuous section of the margin of the upper round the end of the shoe inward over the insole, and means automatically operative to engage the margin of the upper while it is held by said wipers and press it into adhering relation to the insole.
- 50 10. A machine for working an upper over a last and securing it to an insole by adhesion having, in combination, means for laying the margin of the upper over the insole and for holding it lightly at the end and at opposite sides of the shoe simultaneously, and means for engaging the margin of the upper while it is thus held and pressing it into adhering relation to the insole.
- 55 11. A machine for working an upper over a last and securing it to an insole by adhesion having, in combination, means for laying the margin of the upper over the insole, a presser member mounted for movement in a path transverse to the plane of the shoe bottom and arranged to engage a portion of the margin of the upper which projects farther inward than said overlaying means, and power means for operating said presser member in time relation to the overlaying means to press the margin of the upper into adhering relation to the insole.

12. A machine for working an upper over a last and securing it to an insole by adhesion having, in combination, end embracing wipers, operating mechanism movable inwardly toward the shoe to cause said wipers to lay the margin of the upper over the insole, and means carried by said operating mechanism for engaging the margin of the upper and pressing it into adhering relation to the insole.
13. A machine for working an upper over a last and securing it to an insole by adhesion having, in combination, a wiper for laying the margin of the upper over the insole, a presser member movable inwardly with said wiper into position for engaging a portion of the margin of the upper which projects inwardly beyond the wiper, and means for operating said presser member to press the margin of the upper into position to adhere to the insole.
14. A machine for working an upper over a last and securing it to an insole by adhesion having, in combination, means for laying the margin of the upper lightly over the insole without substantial pressure against the insole, and means for engaging the margin of the upper and pressing it into position to adhere to the insole while it is thus lightly engaged by the overlaying means, said margin engaging means being mounted for movement in a path oblique to the plane of the shoe bottom to cause it to subject the margin of the upper to an inwardly directed pull.
15. A machine for working an upper over a last and securing it to an insole by adhesion having, in combination, means for laying the margin of the upper over the insole, a presser member arranged to engage a portion of the margin of the upper which projects inward beyond said overlaying means and press it into position to adhere to the insole, and means for moving said presser member in a path oblique to the plane of the shoe bottom to cause it to subject the margin of the upper to an inwardly directed pull.
16. A machine for working an upper over a last and securing it to an insole by adhesion having, in combination, a wiper for laying the margin of the upper over the insole, mechanism movable inwardly toward the shoe to operate said wiper, a presser member carried by said operating mechanism and positioned thereby relatively to the edge of the shoe bottom for engaging the margin of the upper to press it into position to adhere to the insole, means on said operating mechanism for guiding the presser member in a path oblique to the plane of the shoe bottom, and means for imparting operative movement to said presser member.
17. A machine for working an upper over a last and securing it to an insole by adhesion having, in combination, a wiper constructed and arranged to engage a section of the upper extending round the corner and along the side of the end portion of the last and bend it inward over the insole, a presser member arranged to be positioned relatively to the edge of the shoe bottom in the inward movement of said wiper, and means for operating said presser member to press the margin of the upper into position to adhere to the insole.
18. A machine for working an upper over a last and securing it to an insole by adhesion having, in combination, means for embracing the margin of the upper round the end and along the sides of the last simultaneously and for bending it inwardly over the insole, and members supported and guided independently of one another for engaging the end and side portions of the margin while they are held in said inwardly bent condition and for pressing them into adhering relation to the insole.
19. In a machine of the class described, the combination with shoe positioning means, of overlaying means constructed and arranged to embrace the margin of the upper round the end and along the sides of the shoe and bend it inward over the insole, a plurality of presser members arranged to engage portions of the margin which project inward beyond said overlaying means at the end and along the sides of the shoe, and means for operating said presser members to press the margin of the upper against the insole.
20. In a machine of the class described, the combination with shoe positioning means, of members movable laterally of the shoe to bend the margin of the upper inwardly over the insole at opposite sides of the end portion of the shoe, and additional members movable laterally of the shoe to positions over the insole and movable toward the bottom of the shoe for engaging said inwardly bent margin of the upper and pressing it down upon the insole.
21. In a machine of the class described, the combination with shoe positioning means, of overlaying members movable laterally of the shoe to bend the margin of the upper inward over the insole at opposite sides of the end portion of the shoe, presser members arranged to be positioned relatively to the edge of the shoe bottom in the inward movement of said overlaying members, and means for operating said presser members to press the margin of the upper down upon the insole.
22. In a machine of the class described, the combination with shoe positioning means, of a plurality of independently mounted presser members arranged to engage portions of the margin of the upper round the end of the shoe, and means for

moving said members bodily in paths transverse to the plane of the insole to press the margin of the upper against the insole.

23. In a machine of the class described, 5 the combination with shoe positioning means, of a plurality of independently mounted presser members arranged to engage portions of the margin of the upper round the end of the shoe, and means for 10 moving said members bodily in paths oblique to the plane of the insole to cause them to engage the margin of the upper frictionally and press it against the insole while pulling it inwardly from the edge of the shoe bottom. 15

24. In a machine of the class described, the combination with shoe positioning means, of a presser member curved similarly to the edge of the shoe bottom for engagement with a portion of the margin of the upper at the end of the shoe, additional presser members arranged to engage portions of the margin of the upper along the opposite sides of the end portion of the shoe, 20 and means for moving said presser members bodily in paths transverse to the plane of the insole to press the margin of the upper against the insole.

25. In a machine of the class described, 30 the combination with shoe positioning means, of a plurality of presser members for engaging portions of the margin of the upper round the end of the shoe, supports for said members movable laterally of the edge 35 of the shoe bottom to position said members over the shoe bottom prior to their operative pressing movement, and means for moving said members in paths transverse to the plane of the insole to press the margin 40 of the upper against the insole.

26. In a machine of the class described, the combination with shoe positioning means, of a plurality of presser members for engaging the margin of the upper round 45 the end of the shoe, supports for said members movable laterally of the edge of the shoe bottom to position the members over the shoe bottom prior to their operative pressing movement, and means for operating 50 said members to press the margin of the upper against the insole of the shoe, said supports being constructed to guide the several presser members in paths oblique to the plane of the insole.

27. In a machine of the class described, 55 the combination with shoe positioning means, of a presser member for engaging the margin of the upper of the shoe and pressing it against the insole, a support for said member 60 movable laterally of the edge of the insole to position the member over the shoe bottom prior to its operative pressing movement, and means for moving said member in a path oblique to the plane of the in- 65 sole to cause it to engage the margin of the

upper frictionally with an inwardly directed pull.

28. In a machine of the class described, the combination with shoe positioning means, of a presser member constructed to 70 engage a substantial area of the margin of the shoe upper and press it against the insole, and means for imparting operative movement to said member in a path transverse to the plane of the shoe bottom, said member being mounted for self-adjustment to the contour of the bottom face of the insole lengthwise of the edge of the insole. 75

29. In a machine of the class described, the combination with shoe positioning 80 means, of end embracing wipers for gathering and laying the margin of the upper inwardly over the insole of the shoe, and a member curved similarly to the edge of the shoe bottom round the end of the shoe and 85 movable to engage and press the gathered margin of the upper against the insole on the opposite side portions of the shoe bottom.

30. In a machine of the class described, the combination with shoe positioning means, of end embracing wipers for gathering and laying the margin of the upper inwardly over the insole of the shoe, and a member curved similarly to the edge of the shoe bottom round the end of the shoe and positioned for engaging the margin of the upper beyond the inner edges of the wipers and 95 pressing it against the insole on the opposite side portions of the shoe bottom, and means for moving said member in a path inclined to the plane of the insole to cause it to tighten the margin of the upper rearwardly from the end of the shoe. 100

31. In a machine of the class described, 105 the combination with means for positioning a last with an upper and an insole thereon, of grippers for engaging and pulling the upper at the end and at opposite sides of the last, members mounted for movement 110 to lay the margin of the upper inwardly over the insole round the end of the last, a plurality of presser devices for engaging the margin of the upper farther inwardly than said overlaying members and for pressing it against the insole, and power operated mechanism for imparting operative movements to said grippers, overlaying members and presser devices. 115

32. In a machine of the class described, 120 the combination with power operated means automatically operative to pull an upper over a last and to come to a stop with the upper held under tension, and means operative in a subsequent period of the cycle after the 125 machine has been again started to lay the margin of the upper inwardly over the insole of the shoe, of means automatically operative independently of the overlaying means in said last named period of the cycle 130

to engage the margin of the upper and press it into adhering relation to the insole.

33. In a machine of the class described, the combination with shoe positioning means, of end embracing wipers, power means for operating said wipers to lay the margin of the upper of the shoe over the insole, and additional power operated means constructed and arranged to engage and 10 press the margin of the upper into adhering relation to the insole in time relation to the operation of the wipers.

34. In a machine of the class described, the combination with shoe positioning means, of pulling-over means, end embracing wipers, and additional means comprising a device automatically operative in time relation to said wipers to engage and press the 15 margin of the upper round the end of the shoe into adhering relation to the insole.

35. In a machine of the class described, the combination with shoe positioning means, of means for pulling over the upper at the end and at opposite sides of the shoe, 20 and a plurality of presser members movable bodily in different paths at an angle to the plane of the shoe bottom to press the margin of the upper into position to adhere to the insole of the shoe.

36. In a machine of the class described, the combination with shoe positioning means, of means for bending a portion of the margin of the shoe upper inwardly over the insole, means movable in a path trans- 25 verse to the plane of the insole to press said inwardly bent portion of the margin into position to adhere to the insole, and a roll

movable inwardly over the shoe bottom to lay an adjacent portion of the margin of the upper in position to adhere to the in- 40 sole.

37. In a machine of the class described, the combination with shoe positioning means, of means constructed and arranged to bend a portion of the margin of the shoe 45 upper inwardly over the insole, a presser member arranged to engage inwardly bent portion of the margin and press it against the insole, a support for said presser member movable laterally of the edge of the 50 shoe bottom to position said member over the shoe bottom, and a roll carried by said support for engaging an adjacent portion of the margin of the upper and laying it over the insole. 55

38. In a machine of the class described, the combination with shoe positioning means, of end embracing wipers constructed and arranged to lay the margin of the shoe upper round the end of the shoe over the insole, 60 presser members movable in paths transverse to the plane of the insole into engagement with a portion of the margin of the upper which projects inwardly beyond the edges of said wipers to press the margin of the upper against the insole, and rolls constructed and arranged for movement inwardly over the shoe bottom beyond the ends of said wipers to lay additional portions of the margin of the upper over the 65 insole. 70

In testimony whereof I have signed my name to this specification.

BERNHARDT JORGENSEN.

Certificate of Correction.

It is hereby certified that in Letters Patent No. 1,423,613, granted July 25, 1922, upon the application of Bernhardt Jorgensen, of Beverly, Massachusetts, for an improvement in "Machines for Working Uppers Over Lasts," an error appears in the printed specification requiring correction as follows: Page 6, line 22, claim 2, for the word "position" read *relation*; and that the said Letters Patent should be read with this correction therein that the same may conform to the record of the case in the Patent Office.

Signed and sealed this 5th day of December, A. D., 1922.

[**SEAL.**]

KARL FENNING,
Acting Commissioner of Patents.
